UNITED STATES PATENT OFFICE.

FREDERICK W. EAMES, OF WATERTOWN, NEW YORK.

VACUUM-BRAKE APPARATUS.

SPECIFICATION forming part of Letters Patent No. 241,332, dated May 10, 1881.

Application filed October 29, 1880. (No model.) Patented in England February 19, 1879.

To all whom it may concern:

Be it known that I, FREDERICK W. EAMES, a citizen of the United States, residing at Watertown, in the county of Jefferson and State 5 of New York, have invented certain new and useful Improvements in Vacuum-Brake Apparatus, (Case J;) and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification, the same having been 15 patented to me by the government of Great Britain by Letters Patent No. 616, dated February 19, 1879.

My present invention relates to vacuum-brake apparatus; and it consists in the arrangement and construction of two pistons or diaphragms or sacks attached to leverages of different powers, said leverages being provided with a connecting-rod, whereby, upon the air being exhausted from both sacks, pistons, or 20 diaphragms, the levers will be maintained in a state of equilibrium, and upon the admission of air to one of the chambers the balance will be destroyed and the brakes applied.

Figure 1 illustrates a sectional view, showing my improvement, and Fig. 2 a similar view of a modification of the same.

The invention further consists in a novel construction and arrangement of two pistons, diaphragms, or sacks in such a manner that the 35 slack of the brakes may be rapidly taken up by one vessel, upon which another vessel is brought into action, whereby the brakes are set in action with great power.

a a' represent collapsible vessels. The vessels represented in Fig. 1 are of the same diameter, the vessel *a'*, however, being of larger capacity than the other. These vessels or sacks are placed on the opposite sides of an immovable partition, *b*, fitted with a clack-valve, *c*, 40 which opens toward the smaller sack. Attached to the rigid heads of these sacks are levers *d d'*, which are pivoted at *e* to some suitable attachment to the car, and are connected at their outer extremities by a rigid rod, *f*. The 45 pivots *e e*, it will be seen, are so arranged as to give the sack *a* greater leverage than the sack *a'*.

h is a vacuum-tube opening into the smaller sack, and serving to exhaust both sacks through the valve *c* in the partition between them. The 55 pipe *h* also admits air to the sack *a*.

The operation is as follows: Supposing the rod *f* to be rigidly connected to the brakes, or otherwise, on applying the exhaust to the pipe *h* the air contained in the sacks *a a'* will be 60 withdrawn therefrom. During this operation the pressure of air on the head of the sack *a* will, through the arrangement of lever *d d'* and rod *f*, extend the sack *a'*, and thereby hold off the brakes. So soon, however, as air is admitted by the pipe *h* to the sack *a* the reverse 65 action will take place, the clack-valve *c* closing and preventing the admission of air to the sack *a'*. The inward movement of the head of the sack *a'* will cause the rod *f* to move in the 70 direction of the arrow, and thereby put the brakes in action.

In the modification shown in Fig. 2 of the arrangement just described, *a a'* represent two collapsible vessels. The shells of these vessels are preferably formed in one piece, which is rigidly secured to the under side of the car frame or truck, the division between constituting a fixed head. A central opening is made 75 in this head to bring the flexible vessels into 80 communication with each other, and this opening is closed by a clack-valve, *c*. Both vessels are exhausted from the pipe *h*. The diaphragm of the vessel *a* is connected with one of the brake-levers, and it is fitted internally with a 85 stud, *c'*. As this vessel is exhausted to put on the brakes it will collapse and rapidly advance the brakes to their work. At the same time the stud *c'* will strike the valve *c* and open it, thus putting both vessels into communication with 90 the exhaust apparatus. The diaphragm of the second vessel, *a'*, now moving inward under the effect of the exhaust apparatus, will, by reason of its being connected with brake-levers, re-enforce the action of the first vessel 95 and apply the brakes.

It will be obvious that a like result may be obtained by coupling two shells together and causing the movement of the diaphragm of one to bring the other shell into direct connection 100 with the brake pipe or reservoir, the rods of the two diaphragms being connected with the same lever or arrangement of levers.

In all cases the above-named sack or dia-

phragm devices may be attached to supplementary reservoirs, or they may have sufficient capacity to constitute reservoirs of themselves.

5 Having described my invention, what I claim is—

1. In a vacuum-brake apparatus, the combination of two pistons, diaphragms, or sacks provided with the valve *e*, in both of which a vacuum is maintained, with the levers *d d'* of different leverages, and a connecting-rod, *f*, substantially as and for the purpose set forth.

2. A double vacuum-chamber, *a a'*, having a fixed head and valve, *e*, in common, the piston or diaphragm of one chamber, *a*, adapted, by

its inward movement, to open communication between the two chambers, with the exhaust upon a vacuum being maintained in the chamber *a*, substantially as set forth.

3. In a vacuum-brake apparatus, the chambers *a a'*, having a fixed head provided with valve *e* in common, in combination with pipe *h*, communicating with chamber *a*, substantially as set forth.

In testimony whereof I affix my signature in presence of two witnesses.

FRED. W. EAMES.
